UNITED STATES PATENT OFFICE.

LOUIS J. RIPICH, OF CLEVELAND, AND JOHN V. HORN, OF EAST CLEVELAND, OHIO,
ASSIGNORS OF ONE-THIRD TO JACOB KAUFMAN, OF EAST CLEVELAND, OHIO.

SAFETY DEVICE FOR MACHINERY.

1,312,210.

Specification of Letters Patent.

Patented Aug. 5, 1919.

Application filed December 20, 1918. Serial No. 267,615.

To all whom it may concern:

Be it known that we, LOUIS J. RIPICH and JOHN V. HORN, citizens of the United States, and residents of Cleveland, county of Cuyahoga, and State of Ohio, and of East Cleveland, county of Cuyahoga, and State of Ohio, respectively, have jointly invented a new and useful Improvement in Safety Devices for Machinery, of which the following 10 is a specification, the principle of the invention being herein explained and the best mode in which we have contemplated applying that principle, so as to distinguish it from other inventions.

15 The present improvements relate more particularly to the provision of suitable guard means for use in connection with power driven sewing machines and the like, wherein there is belting underneath a table, by means of which power is communicated 20 from a main drive shaft to a supplemental shaft and thence through a clutch (usually operated by means of a pedal) to the sewing machine, proper, or other operating mechanism on top of the table. As is well known, 25 women workers are largely employed in the operation of machinery of this type and there is constant danger that their skirts will be caught in the belting and that in reaching 30 beneath the table, their fingers may be similarly caught. The object of the present invention is to provide a simple and inexpensive design of guard for use in the connection stated, one that may be attached to 35 any stock type of table, and that will at the same time be readily removable, should access be required to the driving pulleys or belt.

To the accomplishment of the foregoing 40 and related ends, said invention, then, consists of the means hereinafter fully described and particularly pointed out in the claims, the annexed drawing and the following description setting forth in detail certain 45 mechanism embodying the invention, such disclosed means constituting, however, but one of various mechanical forms in which the principle of the invention may be used.

In said annexed drawing:—

50 Figure 1 is a transverse section through a table (specifically a sewing machine table of the type previously referred to) showing our improved safety device or belt guard partly in side elevation and partly in section; Fig. 55 2 is a front elevation of the same, the plane of the section of Fig. 1 being indicated there-

on by the line 1—1; and Fig. 3 is an enlarged sectional view of a detail.

As indicated above, the operating mechanism, *e. g.*, sewing machine proper, in machinery of the kind in hand is supported on a table 1, there usually being a number of such machines on a table of indefinite length. Furthermore, the table is usually double, the operators sitting on opposite sides facing 60 each other, with a depression or trough 2 between the two parts of the table into which the finished work is deposited. Of course, only one side need be regarded for the purpose of the present description. 70

The main drive or power shaft 3 extends longitudinally of the table being supported in suitable bearings 4 near the floor and having mounted thereon pulleys 5, one for each machine on the table, from which the power 75 is communicated through a belt 6 to a second pulley 7 mounted on a counter-shaft 8 or otherwise supported directly beneath the forward portion of the table 1. The driving connection from the latter to the machine on 80 top of the table is usually through a clutch, but this forms no part of the present invention and hence is not illustrated, any more than is the machine in question.

Depending vertically from suitable longitudinally spaced hooks 10 on the under side of the table 1, approximately midway between its front and rear edges, is a main guard member 11 which preferably, as illustrated, takes the form of a wire screen of 85 fairly close mesh, surrounded by a wire frame from which one or more arms or fingers 12 project rearwardly into engagement with the trough 2 or any corresponding depending part of the table. It will thus be 90 seen that while member 11 may be swung outwardly, these arms will prevent it being swung back beyond the vertical position in which it is shown in Fig. 1. In longitudinal extent, member 11 covers the space in front 95 of the individual operator, while it clears the floor below a sufficient amount to allow such floor to be cleaned without interference with broom or mop.

The one end of member 11 (the right- 105 hand end as shown in Fig. 2), extends to a point adjacent to the belt 6 whereby the two pulleys 5 and 7 are connected, the upper pulley and the forward upper portion of such belt projecting beyond the screen. In 110 order to guard these against contact with the operator's clothes or fingers, a second

guard member 15, likewise preferably made of wire netting and of shallow basket form, is hung in front of said pulley and belt portion, being similarly swingably attached at 5 its upper end to hooks 16 on the under side of the table, close to the front edge of the same. At its lower end, this last-named member is formed with a hooked fork 17, or equivalent means adapted to inter-engage 10 with the adjacent corner of the main member 11, (see Fig. 3). Such second member may be thus engaged, either before or after it is attached to the hooks 16, and is thus not only itself supported in proper position 15 beneath the pulley 7 and forward portion of the belt, but at the same time serves to lock the main guard member in place, *i. e.*, against being swung accidentally forwardly.

From the foregoing description, it will 20 accordingly be evident that our improved safety device may be very quickly and easily attached to any machinery of the general type referred to, it being merely necessary to supply hooks properly spaced and located 25 on the under side of the table, whereupon the two guard members may be hung therefrom and secured together without the use of any tools whatever. Similarly said members may be disengaged from each other 30 and separately raised or detached from the table without tools and on a moment's notice. The protection afforded the operator of the machine, however, is as complete as can be desired, more complete than that secured 35 by many more elaborate constructions, while the cost of manufacturing the device will obviously be low. It will, of course, be understood that the members composing the device may be made of other material 40 than netting, *e. g.*, stamped sheet metal or the like, without departing from the spirit of our invention.

We therefore particularly point out and distinctly claim as our invention:

- 45 1. A guard for a sewing or like machine having a top with driving means, including belt and pulley, located beneath such top, said guard comprising a main longitudinally extending member adapted to be attached to and wholly supported from the under side of such table, and a separate member adapted to be attached to such table forwardly of said main member and to incline rearwardly into engagement therewith, 50 whereby said main member is held in place.
- 55 2. A guard for a sewing or like machine having a top with driving means, including belt and pulley located beneath such top, said guard comprising a main longitudinally extending member adapted to be detachably secured to and wholly supported from the under side of such table, and a separate member adapted to be detachably secured to such table forwardly of said main member and to incline rearwardly into en-

gagement therewith, whereby said main member is held in place.

3. A guard for a sewing or like machine having a top with driving means, including belt and pulley, located beneath such top, 70 said guard comprising a main longitudinally extending member adapted to be detachably swingably secured to and wholly supported from the under side of such table, means on said member adapted to engage 75 with said table to prevent swinging of the same rearwardly, and a separate basket-like member adapted to be swingably detachably secured to such table forwardly of said main member and to incline rearwardly into engagement therewith, so as to prevent swinging 80 of said main member forwardly.

4. The combination with a sewing or like machine having a top with driving means, including belt and pulley located beneath 85 such top, of a guard comprising a main longitudinally extending member attached to and wholly supported from the under side of said table laterally adjacent to such belt and pulley, and a separate member attached 90 to and wholly supported from said table in front of such belt and pulley and thence inclining rearwardly and downwardly into engagement with said main member, whereby the latter is held in place. 95

5. The combination with a sewing or like machine having a top with driving means, including belt and pulley located beneath such top, of a guard comprising a main longitudinally extending member detachably 100 swingably secured to and wholly supported from the under side of said table laterally adjacent to such belt and pulley, means on said member adapted to engage with said table to prevent swinging of the same rearwardly, and a separate basket-like member detachably swingably secured to and wholly supported from said table in front of such belt and pulley and thence inclining rearwardly and downwardly into engagement 105 with said main member, so as to prevent swinging of the latter forwardly.

6. The combination with a machine table having driving means, including belt and pulley, located beneath the top of said table, 110 of longitudinally spaced hooks on the under side of such top, to one side of such belt and pulley, a guard comprising a main longitudinally extending member detachably swingably secured to and wholly supported from said hooks, other longitudinally spaced hooks in front of such belt and pulley, and a separate basket-like member detachably swingably secured to and wholly supported from said last-named hooks and thence inclining rearwardly and downwardly into engagement with said main member, whereby the latter is held in place. 115

7. The combination with a machine table having driving means, including belt and 120

pulley, located beneath the top of said table, of a guard comprising two members secured to and wholly supported from the under side of said table at different points transversely 5 of said table and interengaging at their lower ends so as to be held in desired position with reference to a vertical plane.

8. The combination with a machine table having driving means, including belt and 10 pulley, located beneath the top of said table, of a guard comprising two members secured

to and wholly supported from the under side of said table at different points both transversely and longitudinally of said table, one of said members inclining relatively to the other and interengaging with the lower end thereof, whereby said members are held in place. 15

Signed by us, this 17th day of December, 1918.

LOUIS J. RIPICH.
JOHN V. HORR.
